UNITED STATES PATENT OFFICE.

WILLIAM YOUNG, OF DETROIT, MICHIGAN.

RAILWAY-JOINT.

1,350,129.

Specification of Letters Patent. Patented Aug. 17, 1920.

Application filed January 24, 1920. Serial No. 353,892.

To all whom it may concern:

Be it known that I, WILLIAM YOUNG, a citizen of the United States, residing at Detroit, in the county of Wayne and State of Michigan, have invented certain new and useful Improvements in Railway-Joints, of which the following is a specification.

This invention relates to railway joints, and has for its object to provide a joint improved in various respects as will more fully appear from the following description.

A special feature of the joint is that it eliminates the pounding of wheels as they pass over the joint, the meeting ends of the rails being halved and lapped so that the ends are strengthened at the lap by embossed or thickened webs, giving a large amount of metal at the joint, and making the joints as strong or stronger than the remainder of the rail.

Furthermore, the lapped portions of the strengthened web are provided with an interlocking tongue and groove which extends lengthwise between the lapped ends, and prevents relative up and down movement of the meeting ends of the rails, and insures a smooth and even rail head, and prevents high or low rail ends.

I also provide a metal bridge piece which underlies the joints and which the bases of the rails are united to by interlocking joints, the bridge piece having flanges with which the joint is engaged and which prevent any lateral movement of the rail ends. With these parts are associated fish plates or tie bars which interlock with the bridge piece and which are recessed to receive the enlargements at the joint, and the construction is such that when the fish plates are tightened their lower flanges are drawn into a close engagement with grooves in the flanges of the bridge piece. These fish plates also cover or inclose the heads of the bolts which connect the ends of the rails, on one side, and on the other side the fish plate has recesses which receive the nuts of those bolts and act to lock the same.

Other features of novelty and improvement will be apparent from the following description and the accompanying drawings in which Figure 1 is a top plan view of the joint. Fig. 2 is a side elevation. Fig. 3 is a cross section on the line 3—3 of Fig. 2. Fig. 4 is a perspective view of one of the fish plates removed from the joint. Fig. 5 is a perspective of the end of one of the rails.

Referring specifically to the drawings 6 indicates the end of each of the rails. These ends are halved vertically and lapped, as indicated at 7, and the lapped part of one rail has a longitudinal tongue 8, which fits in a corresponding groove 9, in the end of the other rail. Several of these interlocking tongues and grooves may be provided if desired. The end of each rail is enlarged or thickened as indicated at 10, this enlargement extending throughout the lapped part of the rails and for several inches beyond, the enlargement being additional to or formed upon the web of the rail. When so lapped, the ends are connected by the track bolts 11, extending through the thickened webs. The rail ends joined in the manner indicated rest upon bridge plate 12, which has a flange 13, standing at each side edge, 75 and the edges of the rail base abut sidewise against the lower part of these flanges. The rails are further connected by fish plates or tie plates 14. The ends of these plates extend beyond the thickened parts 10, of the rails, and are secured to the webs of the rails by bolts 15, and the tie plates are recessed on the inner side as shown at 16, to receive and inclose or cover the enlargements 10, 80 and the tie plates also have lower flanges 17, which extend outwardly and downwardly and rest upon the rail bases, and the outer edges of the flanges 17, engage in grooves 18, formed on the inner side of the flanges 13 on the bridge piece 12. The fish plate on one side incloses and completely covers the heads of the cross bolts 11. The fish plate on the other side has squared holes 19, which receive the nuts 20 on said bolts 11, and consequently prevent the nuts from turning off 95 except after removal of the fish plate.

Furthermore, when the fish plates are applied and drawn up tight by the bolts 15, by their engagement in the grooves 18 act as levers or cams and create a pressure downward on the bases of the rails thereby clamping the latter against the bridge piece 12, and pressing them downwardly, so to speak. This action is highly advantageous for holding the rail ends and bridge piece together. 100 The bridge piece will be spiked to the ties in the usual manner, the spikes being preferably located at the ends of the bridge piece, at recesses 21, formed for that purpose.

A joint so formed will be practically as strong and rigid as a solid rail, and will

- avoid the many disadvantages known to result from the ordinary form of rail joints. By eliminating low and uneven joints track spreading will be largely prevented, as it will prevent the side-sway or lurch which is the main cause of that condition. The interlocking engagement of the parts is such that they will remain together and in usable condition even if one or more of the bolts are broken. It will be noted that the lapped ends of the rails are bolted together by the inner set of bolts 11, and the ends are also connected by the fish plates and the outer set of bolts 15.
- 15 I claim:
1. A rail joint, comprising rails having lapped and thickened ends fastened together, and fish-plates connecting the rails and recessed on the inner side to inclose said thickened parts.

2. A rail joint comprising lapped rail ends bolted together, and fish-plates connecting the ends, one of said plates being recessed to inclose the heads of the bolts and the other plate having openings inclosing and locking 25 the nuts on said bolts.

3. A rail joint comprising lapped and thickened rail ends bolted together, fish-plates connecting the rails and inclosing the thickened ends thereof, and a base plate on 30 which said ends rest and having edge flanges in interlocking engagement with the lower edges of the fish-plates.

In testimony whereof, I affix my signature in presence of two witnesses.

WILLIAM YOUNG.

Witnesses:

ANNA OSGOOD,
IDA HAGEN.
